[57] CLAIM

The ornamental design for a container seal, as shown
and described.

DESCRIPTION

FIG. 1 is a top perspective view of a container seal
showing the new design;

FIG. 2 is a top plan view thereof;

FIG. 3 is a bottom perspective view thereof;

FIG. 4 is a bottom view thereof;

FIG. 5 is a side view thereof, all sides being the same;

FIG. 6 is a diametric cross-section thereof;

FIG. 7 is a top perspective view of a variation thereof;

FIG. 8 is a top plan view of the variation;

FIG. 9 is a bottom perspective view of the variation;

FIG. 10 is a bottom plan view of the variation;

FIG. 11 is a side view of the variation, all sides being the
same; and,

FIG. 12 is a diametric cross-section of the variation.
